UNITED STATES PATENT OFFICE

124,969

DESIGN FOR AN ADVERTISING SIGN

David N. Grosberg, University City, Mo.

Application November 12, 1940, Serial No. 96,464

Term of patent 14 years

To all whom it may concern:

Be it known that I, David N. Grosberg, a citizen of the United States, residing at University City, county of St. Louis, State of Missouri, have invented a new, original, and ornamental Design for an Advertising Sign, of which the following is a specification, reference being made to the accompanying drawing, forming a part thereof, in which Figure 1 is a front elevational view,

Figure 2 is an edge view, and Figure 3 is a transverse sectional view on approximately the line 3—3, Figure 1, of an advertising sign embodying my new design.

I claim—

The ornamental design for an advertising sign, substantially as shown.

DAVID N. GROSBERG.
